UNITED STATES PATENT OFFICE.

MARTIN L. SENDERLING, OF JERSEY CITY, NEW JERSEY.

DESIGN FOR A KING-BOLT.

SPECIFICATION forming part of Design No. 30,319, dated March 7, 1899.

Application filed February 7, 1899. Serial No. 704,861. Term of patent 7 years.

To all whom it may concern:

Be it known that I, MARTIN L. SENDERLING, a citizen of the United States, and a resident of Jersey City, in the county of Hudson and State of New Jersey, have invented and produced a new and original Design for a King-Bolt, of which the following is a specification, reference being had to the accompanying drawings, forming a part thereof.

10 The leading features of my design consist in a king-bolt having a head presenting substantially a semicylindrical form in side elevation and a rectangular form in edge elevation and top plan and a flange or collar presenting substantially a rectangular form in side and edge elevation and a cylindrical form in top plan.

15 In the accompanying drawings, Figure 1 represents a side elevation of a king-bolt, the leading features thereof being represented in full lines and the balance in dotted lines.

Fig. 2 is a side elevation of the same, and Fig. 3 is a top plan view.

25 A designates the head, which presents substantially a semicylindrical form in side elevation and a rectangular form in edge elevation and top plan.

30 B designates the flange or collar, which presents substantially a rectangular form in side and edge elevations and a cylindrical form in top plan.

What I claim is—

The design for a king-bolt substantially as shown and described.

35 In testimony that I claim the foregoing as my invention I have signed my name, in presence of two witnesses, this 3d day of February, 1899.

MARTIN L. SENDERLING.
